[57] CLAIM

The ornamental design for a combined bottle and cap, substantially as shown and described.

DESCRIPTION

FIG. 1 is a perspective view of a combined bottle and cap showing my new design;

FIG. 2 is an elevation view thereof, the opposite side being the same in appearance;

FIG. 3 is an elevation view thereof looking from the right side of FIG. 2, the opposite side being the same appearance;

FIG. 4 is a top plan view thereof;

FIG. 5 is a bottom view thereof;

FIG. 6 is a perspective view showing a modified form of my new design;

FIG. 7 is an elevation view thereof, the opposite side being the same in appearance;

FIG. 8 is a top plan view thereof;

FIG. 9 is an elevation view thereof looking from the right side of FIG. 7, the opposite side being the same in appearance; and

FIG. 10 is a bottom view thereof.
